PORTABLE TILT-TABLE

Arthur Zampini, Flushing, N. Y.

Application November 4, 1952, Serial No. 22,116

Term of patent 14 years

(Cl. D5—4)

To all whom it may concern:

Be it known that I, Arthur Zampini, a citizen of the United States, residing at Flushing, Queens County, State of New York, have invented a new, original, and ornamental Design for a Portable Tilt-Table, of which the following is a specification, reference being had to the accompanying drawing, forming a part hereof.

Fig. 1 is a side elevational view of a portable tilt-table embodying my new design, the opposite side appearing the same;

Fig. 2 is a plan view thereof;

Fig. 3 is an elevational view of the rear end; and

Fig. 4 is a front elevational view.

I claim:

The ornamental design for a portable tilt-table, as shown and described.

ARTHUR ZAMPINI.
